EXHAUST HEAD

Oliver Mann, Danvers, Mass., assignor to Sylvania Electric Products Inc., Salem, Mass., a corporation of Massachusetts

Application December 13, 1950, Serial No. 200,527

1 Claim. (Cl. 285—90)

1

This invention relates to apparatus for the manufacture of vacuum devices and, more particularly, to a mechanism through which the exhaust tubes of these vacuum devices are connected to a vacuum pump during their manufacture.

In the manufacture of vacuum devices, such as on the exhaust machine, for example, the devices, through an exhaust tube projecting therefrom, are connected to a vacuum pump for evacuation purposes. It is necessary, therefore, that this connection be made air-tight to insure satisfactory evacuation. In most cases the exhaust tube of the vacuum device projects axially therefrom and is threaded into an end of an exhaust head, fixedly mounted on the machine frame, the other end of the exhaust head being connected to a vacuum pump.

In the manufacture of circular fluorescent lamps from linear lamps, usually the linear lamps have the electrodes sealed in the ends thereof and are then fabricated to circular configuration before final evacuation and gas filling is effected. Thus the exhaust tube projecting from one end of the linear lamp must be offset a sufficient distance relative to the lamp axis to clear the other end of the lamp during the final stages of fabrication to circular configuration. This requirement renders it difficult for an operator to thread the exhaust tube into an exhaust head fixedly mounted on the machine frame. The fact that the end of the lamp from which the exhaust tube extends is usually the end which is gripped by jaws or some similar device to hold the lamp on the machine and these jaws are fixedly mounted on the machine frame adds to the difficulty because, with two fixed points, viz., the jaws for holding the lamp, and the exhaust head, the exhaust tube must be offset perfectly to avoid force fitting and excessive exhaust tube breakage. Even with perfectly offset exhaust tubes, some breakage occurs due to machine vibration.

It is, therefore, an object of my invention to provide an exhaust head, particularly adapted for use with offset exhaust tubes but not limited thereto, which avoids the difficulties mentioned above.

Another object of my invention is to insure the attainment of an air-tight seal between the exhaust tube of a vacuum device and a vacuum line.

A feature of my invention is the provision of a "floating" exhaust head which may be manipulated into position to be drawn over the free end of an exhaust tube wherever it may lie.

The exhaust head of my invention comprises a body member with an opening therein and a re-

2

silient tube disposed in this opening, the outside wall of the resilient tube and the wall of the opening in the body member defining a chamber which is connected to a source of fluid (gas or liquid) under pressure.

In a specific embodiment of my invention, the body member is provided with top and bottom cover plates, each cover plate having a tapered boss, upstanding on the inside face thereof, which fits snugly into the respective ends of the resilient tube in the body member. The bottom cover plate has an aperture therein, extending from the outside face thereof and in register with the boss on the inside face thereof, through which the exhaust tube of a vacuum device may be inserted. The top cover plate has a short metal tube upstanding on the top face thereof, in register with the boss on the inside face thereof, which is connected to a flexible vacuum hose.

A specific embodiment of my invention is shown in the accompanying drawing in which:

Figure 1 is a fragmentary plan view of a station on a rotatable turret type machine showing a specific embodiment of the exhaust head of my invention, the air line hose and the means through which it is connected to the head being omitted for clarity of illustration.

Figure 2 is a fragmentary sectional view of Figure 1 with the exhaust head shown in section.

Figure 3 is an exploded, half-sectional, perspective view of the exhaust head.

The rotatable turret machine with which the exhaust head of my invention may be employed may be of the type shown in the co-pending application of Sandford C. Peek, Jr., et al., Serial No. 200,621, filed December 13, 1950 and entitled "Apparatus for Bending Linear Glass Tubing."

In this machine, the turret ring plate 1 has a plurality of blocks 2, one of which is illustrated in the accompanying drawing, mounted equidistant from one another about the top face thereof. A supporting web 3 is mounted on the block 2 and a lamp holder 4 is mounted on the web 3. The lamp holder 4 comprises a fixed jaw 5 attached to the top of the web 3, a movable jaw 6 pivotally mounted at 7 on the web 3, and a lever 8 pivotally mounted at 9 on the web 3 for opening and closing the movable jaw 6 with respect to the fixed jaw 5. A lamp 10 is held by the lamp holder 4 by closing the jaws 5 and 6 thereof about the metal cap 11 on the end of the lamp 10. The lamp 10 has an offset exhaust tube 12 projecting from an end thereof. The free end of this exhaust tube 12 extends into an exhaust head 13.

The exhaust head 13 comprises a body member 14 with an opening 15 therein extending from top to bottom and a resilient tube 16 disposed in the opening 15, the outside wall of the tube 16 and the wall 17 of the opening 15 defining a chamber 18. The chamber 18 is connected to a source of fluid under pressure through a suitable coupling or elbow, such as metal tube 19, which extends through the body member 14 and into the chamber 18. The body member 14 is provided with a vent 33 which functions as a bleeder for a small current of air for cooling the chamber 18 and particularly the resilient tube 16. The bottom face of the body member 14 is counterbored to provide a shoulder 20 on which the flange 21 of the resilient tube 16 seats. The bottom face of the body member 14 is provided with a cover plate 22. The cover plate 22 has an aperture 23 therein and a tapered boss 24 upstanding on the inside face thereof. The top face of the body member 14 is provided with a cover plate 25 which has a tapered boss 26 on the inside face thereof and a short metal tube 27 upstanding on the top face thereof, in register with the boss 26, which is connected to a flexible vacuum hose 28.

In assembling the exhaust head 13, the resilient tube 16 is threaded into the opening 15 in the body member 14, from the bottom thereof, until the flange 21 on the resilient tube 16 seats on the shoulder 20 in the body member 14. The bottom cover plate 22 is positioned by inserting the tapered boss 24 upstanding thereon into the bore of the resilient tube 16 until the inside face of the cover plate 22 engages the adjacent face of the body member 14. The cover plate 22 is then attached to the body member 14, such as by screws 29 for example. The top cover plate 25 is then positioned by inserting the tapered boss 26 upstanding thereon into the bore of the resilient tube 16 until the inside face of the cover plate 25 engages the adjacent face of the body member 14. The cover plate 25 is then attached to the body member 14, such as by screws 30 for example.

After the exhaust head 13 has been assembled it is connected to the apparatus with which it is employed. The free end of a flexible hose 31, connected to a source of fluid under pressure, such as air for example, is drawn down over the metal tube 19 which extends into the chamber 18 in the exhaust head body member 14, thereby connecting the chamber 18 to a source of air under pressure.

The free end of the flexible vacuum hose 28, which extends through a guide bracket 32 mounted on the block 2 on the turret ring plate 1, is drawn down over the metal tube 27, thereby connecting the bore of the resilient tube 16 therethrough to a vacuum pump (not shown).

In positioning a lamp 10 on the machine, the metal cap 11 on the end thereof is placed between the jaws 5 and 6 and the jaws are closed by movement of the lever 8. The exhaust head 13, which has considerable freedom of movement since it is mounted on an end of flexible hose 28, is then manipulated into position so that the aperture 23 in the bottom thereof is in register with the free end of the exhaust tube 12 and the exhaust head is then drawn down over the exhaust tube 12 until the exhaust tube 12 extends a considerable distance into the bore of the resilient tube 16.

With the lamp 10 thusly connected to the exhaust head 13, air under pressure is introduced into the chamber 18 through hose 31 and metal tube 19, thereby causing sufficient deformation of the resilient tube 16 to effect an air-tight seal between the resilient tube 16 and the lamp exhaust tube 12 which lies in the bore thereof. Prevention of air leakage at the ends of the resilient tube 16 is assured by the force fitting of the tapered bosses 24 and 26 into the bore at the ends thereof. The provision of a shoulder 20 on which the flange 21 of the resilient tube 16 seats further insures an air tight seal because it avoids excessive deformation of the resilient tube 16 which might occur when the tapered boss 24 is force-fitted into the bore thereof, and prevents this end of the tube 16 from being pushed up into the opening 15 in the body member 14.

Although in the description of the specific embodiment of my invention illustrated in the drawing, the fluid pressure medium is identified as air, a liquid fluid may also be employed without departing from the spirit of my invention.

What I claim is:

An exhaust head comprising: a body member having an opening therein extending from top to bottom thereof, the bottom face of said body member having a counterbore defining a shoulder therein surrounding the opening, the opening in the upper face being cylindrical; a resilient tube having a bore initially of uniform cross section throughout its length disposed in said opening and extending from top to bottom thereof, said resilient tube having a flange formed on one end thereof, the opposite end of said tube being cylindrical to fit within the cylindrical opening in the upper face, said flange seating on said shoulder, the outside wall of said resilient tube and the wall of the opening in the body member defining a chamber in the body member; a rigid tube connected to a side of said body member, the bore thereof being in communication with the chamber in the body member, a cover plate attached to the bottom face of said body member and comprising means to clamp said flange against said shoulder, said cover plate having an inwardly tapered aperture therein and a hollow externally tapered boss upstanding on the inside face thereof extending into the bore of said resilient tube, said boss being in register with said aperture; and a second cover plate attached to the top face of said body member, said second cover plate having an externally tapered boss with a bore therethrough, said boss upstanding on the inside face thereof extending into the bore of said resilient tube, and a rigid tube upstanding on the outside face thereof adapted to be inserted within a resilient tube, the bore of said rigid tube being in register with the bore of said tapered boss.

OLIVER MANN.
